REVOLVING TABLE

Filed Oct. 20, 1926.

Inventor

Anton Keipp

By his Attorney

Marvin *Alain*

UNITED STATES PATENT OFFICE

ANTON KEIPP, OF MANSFIELD, OHIO

REVOLVING TABLE

Application filed October 20, 1926. Serial No. 142,795.

This invention relates to tables and more particularly to such supports of the revolving type.

One of the objects of this invention is to provide a revolving table having means to prevent a too speedy revolution of the table top whereby the danger of articles placed thereon being thrown off by centrifugal force, is avoided.

10 A further object is in the provision of a table of the type described that is substantially rigid in construction and can be manufactured at a relatively low cost when compared with existing revolving tables.

15 These and other minor objects are accomplished by the novel construction, combination and arrangement of parts hereinafter described and illustrated in the accompanying drawing, forming an important component of this disclosure, and in which:—

Figure 1 is a top plan view of the device, the top of which is partially broken away to show the under construction.

Figure 2 is a sectional view taken on line 25 2—2 of Figure 1.

Figure 3 is a fragmentary transverse sectional view taken on line 3—3 of Figure 1.

In the drawing, the numeral 10 designates a circular hub provided with a short central post 11, there being a plurality of radially extending spokes 12 integrally formed with the hub and an outer rim 13, the spokes each having a semi-spherical recess 14 in their upper surfaces near their outer ends.

35 Secured to the rim 13 at spaced intervals is a plurality of legs 15.

The hub 10 carries the usual form of ball bearing 16 on which is mounted a top circular hub 17 having a central opening 18 to receive the post 11.

The hub 17 also has a plurality of radially extending spokes 19 terminating in an outer rim 20.

Secured to the rim 20 by screws 21 is a circular table top 22, its edges overhanging both the top and bottom rims.

Fixed on the underside of one of the spokes 19 is a downwardly extending flat spring 23 carrying at its free end a ball 24 in the path 50 of recesses 14 so that when the table is ro-

tated, the speed will be retarded because of the engagement of the ball 24 with the recesses 14.

Thus it may be seen that a simple revolving table has been disclosed incorporating means to check the speed of its revolution in order to prevent centrifugal force from throwing off articles placed on the table top.

Although the foregoing is descriptive of the preferred form of my invention, it is to be understood that the same is not to be interpreted as limitative, since minor changes in construction, etc., may be made without the exercise of invention or departing from the claim hereto appended.

Having thus described my invention, what I claim as new and desire to secure by Letters Patent, is:—

A revolving table comprising a lower support, an integral, central post on said support, an upper support mounted over said post, said lower support having a plurality of recesses in its under face, anti-friction bearings intermediate said supports, legs on said lower support, a top plate on said upper support, a flat spring depending from said upper support and means on said flat spring engageable with the recesses to check the revolutionary speed of said table.

In witness whereof I have affixed my signature.

ANTON KEIPP.
